DIVIDING STRIP ANCHOR

Samuel C. Awbrey, Kansas City, Mo.

Application January 7, 1935, Serial No. 605

8 Claims. (Cl. 94—17)

This invention relates to dividing strips for cementitious floors and the means for anchoring such strips in position prior to and during the laying of the floor material, and the primary object is to provide unique, novel and efficient anchoring means that will combine with the floor strip in such fashion as to securely hold it against displacement after having been associated therewith at the point of installation without use of special tools or equipment.

One of the important aims of the invention is to provide a strong, yet relatively inexpensive anchoring means for floor strips, which includes a unitary structure having parts arranged so that the floor strip is engaged by a plurality of staggered elements to maintain the strip against tipping or lateral displacement, some of said elements having parts that engage the dividing strip in a way that will preclude lifting of the strip from the base after the same have been assembled.

Other objects of the invention include providing an anchor for dividing strips that may be stamped from a single piece of sheet metal; have an upstanding wall on a base wall that is slit and angled outwardly to afford strip-engaging members which permit easily associating strip and anchor, yet will snugly engage the sides of the strip when the same is disposed in the working position; and have an upstanding ear formed on the base plate of the anchor to hold the dividing strip in place against the edges of the upstanding wall formed by the slitting thereof, and which engage opposite sides of the said strip.

Since an anchor embodying the invention contemplated may assume a large number of specific structural forms, the objects fulfilled by the embodiment of these forms in all strip anchors will become apparent during the following specification, referring to the accompanying drawings, wherein exemplifications of many forms are illustrated, and wherein:

Figure 1 is a perspective view of an anchor made in accordance with this invention, with a dividing strip held in proper position thereby.

Fig. 2 is a top plan view of the anchor and strip shown in Fig. 1, but with the parts disassociated from any foundation.

Fig. 3 is a sectional view taken on line III—III of Fig. 2, but with the anchor and strip in the floor material, part of which is broken away for clearness.

Fig. 4 is a perspective view of an anchor and floor strip similar to the anchor of Fig. 1.

Fig. 5 is a perspective view of a modified form of anchor, supporting a specific type of strip.

Fig. 6 is a top plan view of the assembly shown in Fig. 5, the anchor having different forms of securing means.

Fig. 7 is a side elevation of the anchor and strip shown in Fig. 6.

Fig. 8 is a perspective view of still another form of anchor embodying the invention.

Fig. 9 is a perspective view of anchor and strip, illustrating the same in position on a wooden base.

Fig. 10 is a perspective view of yet another form of anchor made to accommodate another type of bar.

Fig. 11 is a side elevation of another form of the anchor, holding an even different type of strip.

Fig. 12 is a sectional view taken on line XII—XII of Fig. 11.

Figs. 13, 14 and 15 are side elevations respectively of anchors embodying the invention, but specifically formed to accommodate different strip forms, and

Fig. 16 is a perspective view of a composite anchor embodying the invention and made to properly support dividing strips at their point of intersection in the pattern.

Basically, the anchor per se in every instance comprises a base plate 20, which has means for securing the same in position upon one of two distinct types of supports. Some base plates 20 include both types of securing means and one may be dispensed with if necessary. Where the anchor is used in connection with a concrete support 22, the securing means may be downturned lugs 24 which project into a cement pad or pillow 26 that is supplied by the workmen and placed upon concrete 22 as the location of the anchors is determined.

The function of lugs 24 is clearly illustrated in Fig. 1 and reference to Fig. 9 will teach the manner in which nails 28 pass through apertures 30 formed in base plate 20 for the purpose of attaching the anchor to a wooden floor 32. In all instances the dividing strip is intended to present a longitudinal edge 34 at the upper surface 36 of the floor, which has a cementitious finishing material 38, known to the trade as terrazzo. The thickness of this finishing material is substantially the same as the width of each of the several types of dividing strips and since the dividing strips per se present different laterally extending structures for the purpose of forming transverse shoulders, the specific anchor for each type of strip is altered accordingly.

In all instances, however, the anchor has an upstanding wall 40 slit or slotted intermediate its ends to present an edge 42 and an edge 44. The anchor is further slit longitudinally along the line of connection between wall 40 and base plate 20 so that a wing portion 46 may be created by bending outwardly that part of wall 40 adjacent the first mentioned slit or slot which forms edges 42 and 44.

10 In bending out wing 46, edges 42 and 44 are drawn apart and a relatively wide gate or distance between these edges 42 and 44 is provided which permits insertion of the respective dividing strip in all instances. Wall 40 is preferably created along one edge of base plate 20, and this wall, together with edges 42 and 44 should extend vertically perpendicularly to base plate 20 so that when the respective dividing strip is inserted, it will likewise be held in such relation to plate 20. Observation of the drawings teaches that edges 42 and 44 are not directly opposed and to fulfill one of the broader objects of this invention, there is formed on each anchor and from the base plate 20 thereof, an upstanding ear 48 15 that may be struck from or otherwise integrally created, upon plate 20. This ear 48 is, in all instances, intermediate wall 40 along one longitudinal edge of plate 20 and the other edge of said plate. This ear 48 engages the same side of the dividing strip as does edge 42 on wing 46 and, manifestly, edge 44 engages the opposite side 20 of the respective dividing strip and there is presented elements in staggered relation that engage sides of the strip, with alternate elements 25 engaging opposite sides of the strip. Not only will the structure defined to this point allow quick and easy insertion of the respective dividing strip, but it will be secured against lateral displacement and held substantially perpendicular to plate 20.

Because of the hereinbefore mentioned variation in the laterally extending shoulder-forming portions on the various types of strips, the strip-engaging edges 42 and 44, and in some instances 45 ear 48, must have special shoulder-engaging parts created thereon. In the instance shown in Figs. 1, 2 and 3, the dividing strip has a longitudinally formed embossment 50 that presents a transverse shoulder on each side of the strip.

50 Edge 42, therefore, has a projection 52 that extends into embossment 50 and edge 44 has a notch 54 to which the embossment extends. Ear 48 has a projection 56 which also extends into embossment 50 and these overhanging parts will 55 obviously preclude lifting of the dividing strip from its anchor.

In Fig. 4, projection and notch 52 and 54 respectively is present to enter and receive respectively, embossment 50, but ear 48 is of different 60 form and without an overhanging part.

In Figs. 5, 6 and 7, the dividing strip has outwardly punched anchoring elements 58 that extend laterally to one side of the strip. A notch 60 is formed inwardly from edge 44 to receive one of these elements as the strip is moved longitudinally between edges 42 and 44 when the anchor is being positioned. The shoulder 62 formed by punching elements 58 from the strip affords a transverse surface over which projection 64 on ear 70 48 might extend. Obviously, no lifting of the dividing strip can take place after the parts are associated as described and illustrated in these three last mentioned figures.

In Figs. 8 and 9 the dividing strip is similar 75 to that illustrated in Figs. 1 to 4 inclusive and

has the same embossment 50 to engage projection 52 and notch 54 as before set down. In this form, however, ear 48 has its wider surface facing the side of the dividing strip and its projection 66 is merely a transverse corrugation that extends into 5 embossment 50.

In Fig. 10 the form of dividing strip is that having struck-out lugs 68, one of which extends to each side respectively of the dividing strip. Notches 70 and 72, formed inwardly from edges 10 42 and 44 respectively of wall 40, receive the laterally extending lugs 68, as shown. Ear 48 engages one side of the dividing strip, but no overhanging parts are present with regard to the dividing strip and this form of ear. It may be 15 forced against the side of the dividing strip so as to properly function as one of the staggered elements.

The type of dividing strip illustrated in Figs. 11 and 12 is that having laterally extending 20 shoulders 74 continuously along each side thereof and one of these shoulders is engaged by an edge 76 formed by notching wall 40 inwardly from edge 44 and the opposite shoulder 74 is engaged by the lower edge of wing 46, which in this instance is cut away along the lower portion to 25 present such an edge 78. Ear 48 has a projection 80 that overhangs one shoulder 74 and the broad objects of the invention are again met by this specific structure as regards both strip and 30 anchor.

In Fig. 13 the strip has double corrugations 80 and 82 extending to opposite sides of the strip and the first mentioned corrugation 80 enters notch 84 formed in edge 44 of wall 40. Projection 86 35 formed on ear 48 enters this corrugation 80 and a notch 88 formed in edge 42 of wing 46 receives corrugation 82.

In Fig. 14, shoulders 90 and 92 are engaged 40 respectively by lower edge 94 of wing 46, curled portion 96 of ear 48; and edge 98 formed by notching wing 46 at edge 42.

In the form shown in Fig. 15, there are laterally extending shoulders formed on each side of the dividing strip. Shoulders 100 and 102 are engaged 45 respectively by edge 104 and edge 106 and curled portion 108 of ear 48. It is notable in this instance that the shoulders on one side of the dividing strip only are engaged to preclude the lifting of the strip from the anchor. 50

Fig. 16 illustrates a form of composite anchor 55 that is used at the zone of intersection of the dividing strips. These strips are of the form shown in Figs. 1 to 4 inclusive and 8 and 9, and the anchor per se is merely a unitary structure 60 wherein is embodied the base plates 20 that assume the form of a bottom 110 having upstanding walls 112 along each of three sides thereof. Each of these walls has the previously described wing 114 that has a projection 116 for entering 65 the embossment 50 while notch 118 receives the said embossment. Ears 120, having projections 122, assume the same relation with respect to providing staggered engaging elements and when this form of anchor is used at the point of intersection 70 of the strips, one strip passes completely therethrough, while the two strips forming the intersecting line of the pattern abut each side respectively of the continuous strip. The invention is completely embodied in this form and a 75 rigid, effective, and completely satisfactory anchor is produced.

In making the various types of anchors illustrated and described, forming from sheet metal is contemplated. This metal may be slightly re- 75

silient, but since the invention is clearly exemplified in a large number of modified forms, it is obvious that it may be built into anchors having characteristics greatly removed from those specified.

Having thus described the invention, what is claimed as new and desired to be secured by Letters Patent is:

1. An anchor for dividing strips having laterally extending shoulder-forming parts thereon, comprising a base; elements disposed in staggered relation on the base for engaging the faces of said strip with alternate elements engaging opposite faces of the strip; and a part on one of the elements for engaging the said shoulder.

2. An anchor for dividing strips having a laterally extending shoulder formed thereon, comprising a base; elements disposed in staggered relation on the base for engaging the faces of said strip with alternate elements engaging opposite faces of the strip to preclude lateral movement of the strip; and parts on at least one of the elements for engaging the said shoulder to preclude lifting of the strip from the base.

3. An anchor for a dividing strip of the character described comprising a substantially horizontal base; an upstanding wall formed on the base having a vertical slit formed therein; and an upstanding ear on the base in spaced relation to the said wall, adapted to engage one side of the dividing strip when the same is on the base and extending through the said slit to secure said strip to the base.

4. An anchor for dividing strips of the character described comprising a base plate; an upstanding wall formed along one edge of said base plate having a slot formed transversely thereacross; and an upstanding ear struck from said plate adjacent the opposite edge of the latter to engage one side of the strip, a portion of said upstanding wall being angled outwardly at the slot to form a wing having an edge perpendicular to and spaced from the base plate and adapted to engage the side of the strip engaged by the said ear, the other edge of the wall formed by the slotting thereof being in engagement with the other side of the said strip between the said wing edge and ear.

5. An anchor for dividing strips having laterally extending shoulders thereon, comprising a base plate; an upstanding wall formed on the base plate having a slot formed transversely thereacross; an upstanding ear on the base plate

in spaced relation to the said wall, a portion of said wall adjacent said slot being pressed laterally to offset the opposite edges of the wall defining the said slot; and parts formed on the said edges of the wall for engaging the laterally extending shoulders when the strip is in position on the base.

6. An anchor for dividing strips having a laterally extending shoulder thereon, comprising a base plate; an upstanding wall formed on the base plate having a slit formed transversely thereacross; an upstanding ear on the base plate in spaced relation to the said wall, a portion of said wall adjacent said slot being pressed laterally to offset the opposite edges of the wall defining the said slit; and parts formed on the said edges of the wall for engaging the laterally extending shoulders when the strip is in position on the base, said ear having a laterally projecting portion overlying the said shoulder of the strip.

7. An anchor for dividing strips having laterally extending portions formed thereon to create transverse shoulders intermediate the longitudinal of said strip, comprising a base plate; an upstanding wall along one edge of the base plate having a transverse slit formed thereacross perpendicular to the base plate and a slit extending from said transverse slit along the line of connection between base plate and wall toward one end of said wall; an upstanding ear struck from said base plate intermediate the said wall and other edge of said plate; and a wing portion formed on the said upstanding wall by bending outwardly the portion thereof set off by said slits, the edges of said wall created by transversely slitting the same and said ear engaging the sides of said strip and having projecting portions thereon overlying said transverse shoulders to prevent separation of base and strip.

8. A base for dividing strips of the character described comprising an angle plate, one wall having means formed thereon to secure the same to a supporting surface, and a laterally extending ear struck therefrom and extending outwardly to one side thereof; and the other wall having a slit formed transversely thereacross, and a wing created thereon by pressing outwardly a portion of the wall to one side of the slit, said edges of the wall forming the slit being in offset relation and substantially in alignment with one edge of the said ear.

SAMUEL C. AWBREY.
